UNITED STATES PATENT OFFICE.

JOSEPH ROCH, OF DETROIT, MICHIGAN.

WINDOW-SCREEN.

1,311,248.

Specification of Letters Patent. Patented July 29, 1919.

Application filed April 3, 1919. Serial No. 287,167.

To all whom it may concern:

Be it known that I, JOSEPH ROCH, a citizen of the United States, and residing at Detroit, in the county of Wayne and State 5 of Michigan, have invented a new and Improved Window-Screen, of which the following is a specification.

This invention relates to means for guiding and supporting window screens woven 10 of wires or fibers, and its object is to provide means for holding a screen taut and preventing openings along its vertical edges.

This invention consists of a spring roller to tension the spring and wind it up out of 15 the way when not in use and means to stiffen and hold down the lower edge of the screen, and a pair of guide bars secured to the window casing, which bars are convex toward the screen when pulled down and engage and stress the screen throughout their 20 length.

It further consists in the details of invention illustrated in the accompanying drawing and particularly pointed out in the 25 claims.

In the accompanying drawing, Figure 1 is an outside elevation of a window provided with this improved screen. Fig. 2 is a vertical section on the line 2—2 of Fig. 1 on a 30 larger scale. Fig. 3 is a horizontal section through the end of the roller on which the screen is mounted. Fig. 4 is a horizontal section on the line 4—4 of Fig. 1 on a larger scale. Fig. 5 is a perspective view of a 35 fastener for a lower corner of the screen. Fig. 6 is a vertical section through a roller and a case therefor which may be mounted at the top of window casings already in position.

40 Similar reference characters refer to like parts throughout the several views.

In most houses built of wood the outer top piece 1 of the window casing can be removed and there is usually a space several 45 inches in height above the lintel 2. Within this space and secured to the part 1 and extending inwardly are brackets 3 which support a well known spring roller 4 on which the woven screen 5 is mounted, which screen 50 is preferably only slightly narrower than the window opening. This screen is preferably of wire but any other material may be employed. A narrow slot 6 is cut or left between the outer edge of the lintel 2 and

the outer top piece 1 of the casing to permit 55 the screen to move up and down.

The casing is provided with the vertical outer rails 7, inner rails 8 and parting rails 9 secured to the sides 10 of the casing to guide the upper window sash 12 and lower 60 sash 13. Secured at their lower ends to the outer rails 7 are the vertical guide and support bars 14, preferably of resilient wood, whose outer edges are curved outwardly, as shown in Fig. 2. It will usually be found 65 sufficient to have the middle portions of these guides extend about one half inch beyond the ends for a window four feet high.

Near their upper ends, these guide bars may be supported by screws 15 (Fig. 4) that 70 extend through transverse slots 16 in these guide bars and permit the upper ends of the guide bars to swing back when the screen is released and raised and the cross bar 17 at the lower edge of the screen is 75 pulled up across the slot 6.

The lower ends of the curved guide bars 14 are formed with notches to receive the cross bar 17 which permits the screen to engage the outer edges of the guide bars 80 throughout their length. Because of the curvature of these outer edges the screen is pulled tightly against them by the spring roller and is held there even against a considerable wind.

Small pins 18 (Fig. 5) may extend toward 85 each other from the lower ends of the guide bars and may be engaged by hooks 20 pivoted on plates 20^a secured to the ends of the inner face of the cross bar 17 to prevent the 90 lower end of the screen from swinging out. Any desired type of handle may be secured to the cross bar 17 whereby it may be pulled down, dotted lines 22, Fig. 1, indicating the 95 location of the handle.

When the house is already built and it is inconvenient to mount the roller for the screen above the lintel, a small case 24, Fig. 6, may be secured to the lower side of the 100 lintel 25, and this case may have a slot 26 for the screen, the coöperating guide bars and other parts being as before described.

The principal advantage in so mounting the guide bars that the upper part can swing out is that, should one edge of the screen 105 be slightly longer than the other, the slack caused by this excess of length will be taken up by the resilient guide bar on that side.

The proportions and sizes of the various parts of this screen construction may all be changed without departing from the spirit of this invention as set forth in the following claims.

I claim:

1. The combination with a window casing, of a spring roller at one end thereof, a flexible screen adapted to be wound on the roller, means to hold one end of the screen at the opposite end of the casing, and guide bars secured to the sides of the casing and extending across the normal plane of the screen when extended so that the screen will be drawn against said bars by the spring roller.
2. The combination with a window casing, of a spring roller at the upper part thereof adapted to carry a screen, a flexible screen adapted to be wound on the roller, guide bars secured to the sides of the casing and so positioned that the screen will be drawn against the bars when lowered, and means to hold down the lower end of the screen, the edges of the guide bars engaging the screen being convex lengthwise.

3. The combination with a window casing, of a spring roller at the upper part thereof adapted to carry a screen, a flexible screen adapted to be wound on the roller, guide bars secured vertically to the sides of the casing and so positioned that the screen will be drawn against the bars when lowered, and means to hold down the lower end of the screen, the guide bars being resilient and secured at their lower ends and having their upper ends free to move in and out.

4. The combination with a window casing, of a spring roller at the upper part thereof adapted to carry a screen, a screen on said roller and a cross bar at the lower end of the screen, guide bars secured vertically to the sides of the casing and having notches to receive the cross bar and being so positioned that the screen will be drawn against the bars when lowered, the vertical edges of the guide bars engaging the screen being convex lengthwise, and means to hold the cross bar in the notches at the lower ends of the guide bars.

JOSEPH ROCH.
